UNITED STATES PATENT OFFICE.

WASHINGTON B. VANDERLIP, OF OAKLAND, CALIFORNIA.

APPARATUS FOR GENERATING POWER.

1,236,020.

Specification of Letters Patent.

Patented Aug. 7, 1917.

Application filed July 29, 1916. Serial No. 112,111.

To all whom it may concern:

Be it known that I, WASHINGTON B. VANDERLIP, a citizen of the United States, residing at Oakland, in the county of Alameda and State of California, have invented certain new and useful Improvements in Apparatus for Generating Power, of which the following is a specification.

The present invention relates to an improved method and apparatus for generating power by the expansion of the gases generated from the explosion of what are commonly termed "high explosives," such as nitro-glycerin.

15 The invention consists primarily in the generation of power by the utilization of the gaseous volume, generated by the explosion into a suitable container of highly explosive substances, such as nitro-glycerin and which volume is materially expanded by the explosive temperature thereof, whereby great power at little cost is obtained.

20 The present method consists primarily in intermittently exploding or firing given charges or cartridges of explosive mixtures, such as nitro-glycerin or other explosive high in combustion gases and heat units when exploded into a heat insulated chamber, reservoir or container, either separately 25 or in the presence of water and storing and retaining the accumulated gases of explosion therein at a high temperature, and then gradually delivering the stored gases, under pressure, to a suitable engine or motor.

30 35 It has been calculated that one volume of nitro-glycerin when exploded, generates about 12000 volumes of gas at a temperature of approximately eight thousand one hundred and thirty two degrees Fahrenheit, and that this temperature expands the generated gases approximately eight times their volume, so it will be observed that in the utilizing of this explosive in the carrying on of my invention, great power is obtained by

40 45 50 the explosion of a single volume thereof. It has also been calculated that one pound of anthracite coal contains approximately nine thousand three hundred and seventy-nine B. T. U.'s, and that a similar quantity of nitro-glycerin contains over twenty-one millions B. T. U.'s, so it will be observed that from a given quantity of high explosive, much greater power is obtained than from

the use of a like quantity of coal or other fuel now universally employed for power 55 purposes.

In the carrying out of my method, an apparatus provided with a mechanically unseated and pressure actuated check valve, intermediate the firing and storage or accumulating chambers, and opening into the latter, is desirable, the accumulating pressure in the storage or accumulating chamber assisting to seat the valve and the same being actuated intermittently by the successive explosions of the charges or cartridges in the firing chamber and which explode directly against the valve.

With the above mentioned and other objects in view the invention consists of the novel construction and combination of parts hereinafter described, illustrated in the accompanying drawings, and pointed out in the claims hereto appended; it being understood that various changes in the method 70 and apparatus may be made within the scope of the appended claims, without departing from the spirit or sacrificing any of the advantages of the invention.

To more fully comprehend the invention, 80 reference is directed to the accompanying drawings wherein there is disclosed one form of apparatus for carrying out my method, and wherein:

Figure 1 is a view in elevation partly in section of the preferred form of apparatus illustrating the accumulating and storage chamber, the firing chamber, and the cartridge or charge feeding and firing the mechanism.

Fig. 2 is a vertical, longitudinal sectional view of the firing chamber and mechanism, disclosing more particularly the check valve at the muzzle of the firing chamber, the charge positioning ram and the firing pin, 90 and the breech-block for locking the ram in position.

Fig. 3 is a sectional view taken on line 3—3 of Fig. 2.

Fig. 4 is a vertical sectional view of the 100 magazine and charge or cartridge feeding mechanism taken on line 4—4 of Fig. 5.

Fig. 5 is a view in top plan of the magazine.

Fig. 6 is a sectional view of a modified 105 form of barrel and firing chamber, illustrat-

ing a form of rotary valve which may be employed either independently of or in combination with the pressure actuated valve, illustrated in Figs. 1 and 2.

5 Fig. 7 is a view in cross section of the cartridge guiding chambers, taken on line 7—7 of Fig. 2.

Referring more particularly to the several views of the drawings, wherein like characters of reference designate corresponding parts, 1 indicates a suitable base, supporting a suitable accumulating and storage chamber 2 into which the cartridges or charges are directly exploded, and to insure the 15 maximum of safety, the chamber is provided on its interior with the perforated wall surface 3 arranged to provide a compartment 3' directly in front of the muzzle of the barrel which opens thereinto. The said walls 20 are braced by the stays 4 which connect with the outer wall of the chamber. The chamber is preferably formed of the spaced outer and inner walls, A and B, providing a space C, and to prevent the radiation of the heat from 25 the gases contained within the chamber 2, a vacuum is maintained in the space C in any suitable manner. For purposes of illustration, I employ a Venturi tube 5 connecting with the space C through a connection 6, 30 and extending into the said tube is a valve-controlled pipe 7 connecting with the interior of the chamber 2, and through which gases under pressure pass when it is desired to draw the air from the chamber 3. 35 A gage registers the vacuum drawn in the space C.

Extending through the walls A to B of the chamber 1 and opening at its muzzle into the compartment 3' is a barrel 9 formed with 40 a firing chamber 10 extending therethrough and which flares at its muzzle as at 11. An annular cooling chamber 12, Fig. 2 of the drawings, is provided in the barrel surrounding the firing chamber 10 and a circulation 45 of cooling fluid is maintained therethrough by the pipes 13 and 13'.

A tubular charge or cartridge guiding chamber 14' connects with the breech end of the firing chamber 10 and mounted to 50 reciprocate therein, is the cartridge positioning and ejecting ram 14, which carries the firing pin 15 extending longitudinally therethrough, and of a length slightly greater than that of the ram.

55 The ram 14 is reciprocated to intermittently position successive cartridges, each containing a suitable charge of high explosive, within the firing chamber by the following mechanism, illustrated in Fig. 1 60 of the drawings. A crank 16 pivoted as at 17 to a bracket 18 on a frame 19, is slotted as at 20, in one of its arms to receive the pin 21 carried by the outer end of the ram and which projects through and operates in a slot 65 22 in the wall of the cartridge guiding cham-

ber 14', and on each rocking of the crank 16, the ram is reciprocated its full distance.

The other arm of said crank 16 is pivotally connected by a link 23, eccentrically of a suitable wheel 24 supported on a shaft 25 70 and having geared connection with a corresponding wheel 26 carried by a shaft 27, which is driven in any suitable manner as by the worm 28 engaging with the toothed wheel 29, illustrated in dotted lines in Fig. 1. 75 The ram 14 is provided adjacent its end with the cutouts 30, providing shoulders 30'; and when in its forward-most position, is adapted to be locked to withstand the recoil of the exploded cartridge, by a suitable vertically 80 reciprocating breech-block 31 which operates in an opening 32 transversely of the barrel 9. The breech-block 31 is slotted at its upper end as at 33, Fig. 3 of the drawings to receive the solid portion 33' of the ram, and 85 the bifurcated portions 34' of said breech contact with the shoulders 30' when the block is in its uppermost position.

To reciprocate the breech-block 31 in timed relation with the ram 14, to engage 90 the same immediately after the ram has reached its forward-most point of movement, and to release therefrom, immediately prior to the starting of each rearward reciprocation, an arm 34 extends from the underside 95 of the breech-block and operates through a housing 35 inclosing the base of the same. The lower end of the arm 34 is connected through a link 35 with the face of a toothed pinion 35' intermeshing with a gear 36 on 100 the shaft 27.

The shells or cartridges 38, each containing a charge of high explosive, preferably nitro-glycerin, rest one above and upon the other in the magazine 39, disposed vertically 105 above the guiding chamber 14', as in Figs. 1, 2 and 4 of the drawings. The shells are intermittently dropped by gravity from the mechanism 39 into the chamber 14', by the spaced inter-connected reciprocating 110 slides 40 and 40', which operate in transverse grooves 41 in the magazine. A rod 42 fulcrumed at its center as at 43 to a bracket 43' and pivotally connected at its opposite ends to the slides 40 and 40' controls the movement thereof. Extending diagonally across the under face of the lower slide 40, is a guide 42², Figs. 4 and 5 of the drawings, having its front portion hinged as at 43² to swing in a forward direction against the tension of the spring 44' and said hinged portion is prevented from swinging rearwardly beyond the line of the main portion of the guide 42² by the 115 engaging shoulders 44. A pin 45 carried by the ram 14 and projecting through a slot 46 in the wall of the chamber 14' is adapted on its forward movement when the ram is pushing the shell in the chamber 14' toward the firing chamber 10, to engage the front or 120 125 130

hinged portion of the guide 42² and swing the same forwardly, which will permit the pin to pass without actuating the slides. On the return movement of the ram, the pin 45 contacts with the front face of the hinged portion 42³ of the guide 42², causing the shoulders 44 to engage, which prevent the swinging rearwardly of the hinged portion, and the pin is thus caused to travel the full 10 length of the guide 42², and in so doing, forces the lower slide 40 outwardly and the upper slide 40' inwardly, permitting the cartridge between the slides to drop into the chamber 14'. As the pin 45 clears the 15 inner end of the guide 42², a coiled spring 46 coacting with the lower slide 40 again forces the lower slide inwardly, permitting the lowermost shell now supported by the upper slide 40' to drop on to the lower 20 slide 40, and to be fed into the chamber 14' on the next reciprocation of the slides.

As the cartridges are fed into the chamber 14' and are pushed forwardly by the ram 14, the same are fired in the following manner, immediately after the ram is locked 25 by the coöperating breech-block. A hammer 50, Fig. 1 of the drawings, pivoted to a bracket 51 carried by the frame 19, is adapted to strike and operate the firing-pin 30 15 when the ram is in its forward-most position. Coöperating with said hammer is a trigger 52 pivoted as at 53 with one end portion coöperating with a notched seat in the hub 54 of the hammer, and the other end is 35 adapted for coöperating with a finger or releasing lug 55 carried by the periphery of the flange 56 on the toothed wheel 57 mounted on a shaft 58 and driven by a corresponding gear 59 carried by the shaft 27. 40 A spring 60 forces the hammer 50 into contact with the firing pin on the actuation of the trigger 52, and a spring 61 normally maintains the notched end of the trigger in contact with the hub of the hammer. The 45 finger or lug 55 is timed to contact with and operate the trigger 52 to release the same from the hammer 50, immediately after the breech-block 31 is forced upwardly to lock the ram in position, which permits the hammer 50 to strike the firing pin 15 and fire 50 the shell or charge positioned in the firing chamber. It will be observed that the rearward reciprocation of the ram 14 engages the hammer 50 and moves the same to be 55 held in cocked position as in Fig. 1 by the trigger 52.

A check valve 61 having a conical face 62 seating in the conical opening 11 of the firing chamber 10, prevents the escape of 60 the accumulated gases from the chamber 2 through the firing chamber when the ram 14 is moved rearwardly, and to momentarily unseat this valve simultaneously with the firing of each shell the following mechanism is employed. The valve is carried by 65

a frame 63 and from the same extend the guide-rods 64 reciprocating in glands 64' in the barrel 9 and said rods project rearwardly beyond the barrel as in Figs. 1 and 2, where they are connected by the guide-frame 65 sliding on the wall of the chamber 14'. Coiled springs 66 surrounding the guides 64 and positioned intermediate the frame 65 and a suitable rod-guiding frame 67 through which the rods slide, normally 70 maintain the valve seated. A trip lug or arm 68 is carried by the wheel 57 adjacent the lug 55, and said arm 68 is adapted on each rotation of the wheel, to contact with the guide-frame 65 simultaneously with the 75 firing of the positioned cartridge or charge, to unseat the valve, the pressure of the exploding cartridge or charge fully lifting the valve from its seat to permit the escape of the gas volume from the firing chamber 80 85 10 into the accumulating and storing chamber 2.

After the shells are successively fired the same will be withdrawn from the firing chamber 10 into the guiding chamber 14' 90 and ejected therefrom in the following manner. The rim 69 of each shell as successively fed in the chamber 14 is engaged on the forward movement of the ram 14 by a spring catch or finger 70 and rides over 95 the beveled face 71 of a corresponding spring finger or catch 72, projecting upwardly through the bottom wall of the chamber 14', slightly in advance of the magazine and at a point in line with the rear 100 edge of an ejecting opening 73, formed in the top wall of the chamber 14' and of a length slightly greater than that of the shell. After the charge has been fired the exploded shell is rapidly drawn rearwardly by the 105 quick movement of the ram 14 and finger 70, and during its movement the rear face of the rim 69 thereof contacts with the vertical face 74 of the catch 72, which resists the rearward movement of the shell and permits 110 the finger 70 and catch 72 to flip the forward end of the shell upwardly and to eject the same through the opening 73.

A water supply connection 74' having an inlet 75 communicating with chamber 2 and 115 controlled by a valve 76 actuated by a suitable thermostat 77 within the chamber, supplies a given quantity of water to the chamber at all times, to reduce the temperature thereof. The water is admitted into the 120 chamber 2 in the form of a fine spray, and immediately on entering the same will be converted into steam, due to the high temperature of the exploded gases within the chamber, and will add a considerable volume 125 in the form of steam to the gases contained within the chamber.

The accumulated gases under pressure are released from the chamber 2 to actuate any suitable power apparatus through an outlet 130

pipe 78 controlled by valve 79, and said pipe having mounted thereon a pressure gage 80 and a safety valve 81.

In the modified form of barrel disclosed in Fig. 6 of the drawings, a rotary valve 82 is illustrated to control the passage of the exploded gases from the firing chamber into the accumulating chamber 2, and said valve is provided with a port 82' adapted when the valve is rotated by any suitable mechanism connected to the arm 83 of the valve, to align with the bore in the firing-chamber.

In utilizing the above described apparatus for the carrying out of my present method of producing power, charges of high explosive compound are fired into a suitable closed chamber preferably in the presence of water, and are retained therein under a high temperature until released therefrom to operate any suitable source of power.

It will be apparent that owing to the low cost and high results obtained by the use of high explosives great power at little cost is generated.

25 Having thus described my invention, what I claim is:

1. An apparatus for producing power comprising a pressure accumulating and storage chamber, a barrel opening thereinto and provided with a firing chamber, means for intermittently positioning cartridges containing explosive charges within said firing chamber, means for successively exploding said positioned cartridges, means for ejecting the exploded cartridges, a check valve intermediate the firing chamber and said pressure accumulating chamber and seated by the accumulated pressure within said chamber, and a valve-controlled outlet 30 within said chamber for releasing the accumulated pressure therefrom.

2. An apparatus for producing power comprising a pressure accumulating and

storage chamber, a barrel opening into said chamber, and provided with a firing chamber, means for intermittently positioning cartridges containing explosive charges within said firing chamber, means for successively exploding said positioned cartridges, means for ejecting the exploded cartridges, a check valve intermediate the firing chamber and said pressure accumulating chamber and seated by the accumulated pressure within said chamber, means for unseating said valve simultaneously with the exploding of the charge in each cartridge, and a valve controlled outlet within said chamber for releasing the accumulated pressure therefrom. 45 50 55

3. An apparatus for producing power comprising a double walled pressure accumulating and storage chamber, means for drawing a vacuum between the walls of said chamber, a barrel opening into said chamber, and provided with a firing-chamber, 60 means for intermittently positioning cartridges containing explosive charges within said firing-chamber, means for successively exploding said positioned cartridges, means for ejecting the exploded cartridges, a check- 65 70 75 valve intermediate the firing chamber, and said pressure accumulating chamber and seated by the accumulated pressure within said chamber, means for unseating the valve simultaneously with the exploding of the charge in each cartridge, and a valve controlled outlet within said chamber for releasing the accumulated pressure therefrom.

In testimony whereof I have signed my name to this specification in the presence of 80 two subscribing witnesses.
